CARBURETOR

Marion Mallory, Detroit, Mich.

Application December 5, 1935, Serial No. 53,051

11 Claims. (Cl. 261—49)

This invention relates to an improvement in carburetors which has for one of its objects to maintain a considerable vacuum under all operating conditions in and around the fuel nozzle and in the mixing chamber for the purpose of insuring and maintaining complete atomization of the fuel from the time it enters the mixing chamber until it reaches the engine cylinder. At the same time, the fuel which is supplied from the fuel nozzle should be metered in order to insure a mixture of the proper proportions at different positions of the throttle. By this construction, it is possible to supply gasoline through the main nozzle both for idling and for part throttle operation and to thereby eliminate the expensive means for by-passing the fuel around the throttle, which is common practice in plain tube carburetors.

In addition to the main throttle valve, located on the engine side of the fuel nozzle, the invention involves a second valve, which is unbalanced, on the opposite side of the fuel nozzle. This second valve restricts the flow of air for idling and for part throttle operation, but not for full power. It may be said, therefore, that the invention presents the characteristics of an air valve carburetor for part throttle operation and of a plain tube carburetor for full power.

In the accompanying drawing.—

Fig. 1 is a vertical section taken centrally of the mixing chamber and fuel bowl of a carburetor constructed in accordance with the invention.

Fig. 2 is a partial section, similar to Fig. 1, showing a modified form of the invention.

The carburetor as shown is of the down draft type, although the invention is not limited to that type of construction. It comprises a mixing chamber 5 formed with a venturi 6, adjacent to which is a fuel bowl 7 of well known construction, having a fuel inlet pipe 8 with a valve 9 controlled by a float 10. From the bottom of the bowl 7, a fuel passageway 11 leads to a well 12, from which fuel is delivered to a nozzle 13 located within the venturi 6. A throttle valve 14, at the lower end of the mixing chamber 5, is provided with an arm 15, which is actuated in the usual manner through the medium of a rod 16 to open or close the throttle.

The inner end of the arm 15 is extended beyond the axis of the throttle valve, as at 17, and is there connected to a rod 18, which telescopes freely into the end of a rod 19. The other end of the rod 19 is connected to the arm 20 of a second valve 21, which is unbalanced, so that the air flow and the suction of the engine tend to open it when the throttle is partly or wholly open.

The outer end of the arm 20 is connected by a link 22 to a piston 23, which is reciprocable in a dash pot 24, the latter having a bleed 25 opening to the atmosphere to permit the valve 21 under the influence of suction and air flow to slowly follow the opening movement of the valve 14. A by-pass bleed opening 26 is normally closed by a needle valve 27, which is held by a lever 28 pivotally mounted at 29 and acted on by the tension of a coil spring 30. In other words, the valve 21 lags behind the valve 14, temporarily enriching the mixture for part throttle acceleration and thereby dispensing with the need for an accelerating pump. When the throttle valve 14 is opened wide, a cam 31 on the valve axis strikes the lever 28 and positively opens the needle valve 27 against the resistance of the spring 30, thereby permitting the dash pot 24 to vent quickly and preventing the fuel mixture from being too rich on wide open throttle acceleration.

The dash pot 24 also has an air inlet 32 controlled by a relief valve 33, which permits the dash pot to be filled quickly with air as the valve 21 closes with the valve 14.

The amount of fuel supplied to the nozzle 13 is determined by a metering pin 34, which is connected to the arm 15 by a link 35 and which has one side flattened, as at 36, so as to supply an increasing amount of fuel as the throttle is opened. The closing of valve 21 simultaneously with the valve 14 is positively effected by a nut 37 on the rod 18, which engages the lower end of the rod 19. The gasoline supply for idling is determined by the position of the metering pin 34, but this supply may be varied by adjusting the nut 37, thereby determining the idling position of the valve 21 and the degree of vacuum at the nozzle when the engine is idling.

For choking the engine, an arm 38, loosely mounted on the axis of the valve 21, is provided with an arcuate slot 39 which receives a pin 40 secured to the arm 20. A choke rod 41 is connected to the arm 38 and, when moved in the direction of the arrow, positively holds the valve 21 closed when the valve 14 is opened, thereby restricting the supply of air to the fuel mixture.

In the modification shown in Fig. 2, the dash pot 24 is filled with liquid instead of air. That is, it is connected with the bowl 7 by a bleed 45. A larger vent passageway 46 is normally closed by a needle valve 47, acted upon by a spring 48. The needle valve 47, however, is connected by a lever 49 to a rod 50 which is looped around the rod 18. When the throttle valve 14 is opened wide, the nut 37 engages the loop on the rod 18.

and opens the needle valve, thus permitting the dash pot to vent quickly. Upon closing the valves 14 and 21, the relief valve 51 opens, so that the dash pot is quickly refilled through the passage-way 52.

From the foregoing description, it will be understood that the dash pot will always resist the opening of the air inlet valve 21 whenever the throttle valve 14 is partially opened, thereby causing the valve 21 to lag behind. This enriches the mixture during acceleration, by reason of the increased vacuum or suction, as well as insuring complete atomization. It also prevents over-charging of the engine at low speed when the throttle is opened suddenly, but the air flow is not materially restricted when the throttle is wide open for full power and this prevents the mixture from becoming too rich at such time.

It is to be understood that the invention is not limited to the embodiments herein shown and described, but embraces such other modifications as may fall within the scope of the appended claims.

I claim:

1. In a carburetor, a mixing chamber, a throttle valve on the engine side thereof, an air inlet with an unbalanced valve therein adapted to be opened only by the pressure of the air passing through said inlet, said chamber being formed 30 with a venturi between the two valves, a fuel inlet at the narrowest point in the venturi, means for increasing the capacity of the fuel inlet as the throttle valve is opened, means to limit the possible opening of the air inlet valve in proportion to the opening of the throttle valve, and means to temporarily resist the opening of the air inlet valve when the throttle valve is opened quickly.

2. In a carburetor, a mixing chamber, a throttle valve on the engine side thereof, an air inlet with an unbalanced valve therein tending to open under the influence of air flow or mixing chamber suction, said chamber being formed with a venturi between the two valves, a fuel inlet at 45 the narrowest point in the venturi, means for increasing the capacity of the fuel inlet as the throttle valve is opened, means to limit the possible opening of the air inlet valve in proportion to the opening of the throttle valve, and a dash 50 pot connected with the air inlet valve to retard its opening movement when the throttle valve is opened quickly.

3. In a carburetor, a mixing chamber with a throttle valve on the engine side thereof and an unbalanced air inlet valve at the other side adapted to be opened only by air flow through said inlet, said chamber being formed with a venturi between the two valves, a fuel inlet at the narrowest point of the venturi, a metering pin for 60 the fuel supply to said inlet, means connected with the throttle valve and controlling the metering pin to increase the capacity of the fuel inlet as the throttle is opened, a dash pot connected to the air inlet valve to offer temporary resistance to the opening thereof, and a lost motion connection between the throttle and the air inlet valve positively limiting the opening of the latter in proportion to the throttle opening.

4. In a carburetor, a mixing chamber with a throttle valve on the engine side thereof and an unbalanced air inlet valve on the other side, said chamber being formed with a venturi between the two valves, a fuel inlet at the narrowest point of the venturi, a metering pin for the fuel supply to said inlet, means connected with the throttle valve and controlling the metering pin to increase the capacity of the fuel inlet as the throttle is opened, a dash pot connected to the air inlet valve to retard the opening thereof, a lost motion connection between the throttle and the air inlet valve positively limiting the opening of the latter in proportion to the throttle opening, said dash pot having a constantly open vent and a second vent normally closed, and means to open the second vent only when the throttle is opened wide or nearly so.

5. In a carburetor, a mixing chamber having fuel and air inlets, a throttle valve, a valve for the air inlet adapted to be opened by air flow into the mixing chamber, means to limit the possible opening of the air inlet valve in proportion to the opening of the throttle valve, a dash pot connected to the air inlet valve and constituting the sole means to normally oppose its opening to the limit indicated, said dash pot having a comparatively small constantly open vent and a second vent normally closed, and means to open the second vent when the throttle valve is opened wide or nearly so.

6. In a carburetor, a mixing chamber having fuel and air inlets, a throttle valve, a valve for the air inlet adapted to be opened by air flow through said inlet, means to limit the possible opening of the air inlet valve in proportion to the opening of the throttle valve, a dash pot connected to the air inlet valve and constituting the sole means to normally oppose its opening to the limit indicated, said dash pot having a comparatively small constantly open vent and a second vent normally closed, and means to open the second vent when the throttle valve is opened wide or nearly so.

7. In a carburetor, a mixing chamber having fuel and air inlets, a throttle valve, a valve for the air inlet adapted to be opened by air flow through said inlet, means to limit the possible opening of the air inlet valve in proportion to the opening of the throttle valve, a dash pot connected to the air inlet valve and constituting the sole means to normally oppose its opening to the limit indicated, means for metering the flow of fuel through the fuel inlet in synchronism with the opening of said throttle valve, said dash pot having a comparatively small constantly open vent and a second vent normally closed, and means to open the second vent when the throttle valve is opened wide or nearly so.

8. In a carburetor, a mixing chamber, a throttle valve on the engine side thereof, an air inlet with an unbalanced valve therein tending to open under the influence of air flow into said chamber, means to limit the possible opening of the air inlet valve in proportion to the opening of the throttle valve, said chamber being formed with a venturi between the two valves, a fuel inlet at the narrowest point of the venturi, means for increasing the capacity of the fuel inlet as the throttle valve is opened, a dash pot connected with the air inlet valve and constituting the sole means to normally oppose its opening movement when the throttle valve is opened quickly, said dash pot having a comparatively small constantly open vent and a second vent normally closed, and means to open the second vent when the throttle is opened wide or nearly so.

9. In a carburetor, a mixing chamber with a throttle valve on the engine side thereof and an unbalanced air inlet valve at the other side adapted to be opened by air flow, said chamber being formed with a venturi between the two valves, a fuel inlet at the narrowest point of the venturi, a metering pin for the fuel supply to said inlet, means connected with the throttle valve and controlling the metering pin to increase the capacity of the fuel inlet as the throttle is opened, a dash pot connected to the air inlet valve to retard the opening thereof, a lost motion connection between the throttle and the air inlet valve positively limiting the opening of the latter in proportion to the throttle opening, said dash pot having a constantly open vent and a second vent normally closed, and means to open the second vent only when the throttle is opened wide or nearly so.

9. In a carburetor, a mixing chamber with a throttle valve on the engine side thereof and an unbalanced air inlet valve on the other side, said chamber being formed with a venturi between the two valves, a fuel inlet at the narrowest point of the venturi, a metering pin for the fuel supply to said inlet, means connected with the throttle valve and controlling the metering pin to increase the capacity of the fuel inlet as the throttle is opened, a dash pot connected to the air inlet valve to retard its opening, means actuated by the closing movement of the throttle constituting the sole means normally tending to close the air inlet valve and for limiting its opening in proportion to the throttle opening, suction and air flow past the unbalanced air inlet valve constituting the sole means for opening the same, said dash pot having a constantly open vent and a second vent normally closed, and means to open the second vent only when the throttle is opened wide or nearly so.

10. In a carburetor, a mixing chamber, a throttle valve on the engine side thereof, an unbalanced air inlet valve between the mixing chamber and the atmosphere, a lost motion con-

nection between the two valves having in itself no effect on the opening of the unbalanced valve when the throttle valve is opening but positively closing the unbalanced valve in synchronism with the throttle valve as the latter is closed, the air flow past the unbalanced valve constituting the sole means for opening it, and a dash pot constituting the sole means normally resisting the opening of the unbalanced valve when the throttle valve is opened.

11. In a carburetor for internal combustion engines, a mixing chamber having fuel and air inlets, a throttle valve on the engine side of said chamber, a metering pin connected with the throttle valve to increase the capacity of the fuel inlet with the opening of the throttle, an unbalanced valve for the air inlet, a lost motion connection between the throttle valve and the unbalanced valve positively closing the latter as the throttle is closed but releasing it to the influence of the air flow as the throttle is opened, and a dash pot retarding the action of the unbalanced valve in following the opening movement of the throttle valve.
